UNITED STATES PATENT OFFICE.

ALEXANDER BOYNTON, OF SAN ANTONIO, TEXAS.

TELESCORIC AIR VALVE AND OPERATING MEANS THEREFOR.

Application filed December 26, 1923. Serial No. 682,845.

To all whom it may concern:

Be it known that I, ALEXANDER BOYNTON, a citizen of the United States, and resident of San Antonio, in the county of Bexar and State of Texas, have invented certain new and useful Improvements in Telescopic Air Valves and Operating Means Therefor, of which the following is a specification.

This invention relates to telescopic air valves and operating means therefore especially adapted for use in oil and water wells.

The usual practice in pumping wells with air is to introduce air under pressure and through the usual perforations in the lower portion of the tubing so that inrushing air will elevate and discharge the oil. However, in case the well is flooded as a result of the failure of the pumper to pump the same at frequent intervals or for other reasons, the well will not pump from the bottom and it is necessary to elevate the tubing by an expensive process so that it will pump from a higher level. As the oil level drops the tubing may be lowered so that it is adjusted to the new level of oil, and this is repeated until the well again pumps from the bottom.

However, the foregoing operation is expensive and time consuming and therefore an important object of this invention is to provide simple means whereby the oil may be pumped at any level without the necessity of lifting the tubing off bottom.

Further the invention aims to provide simple means whereby the well may be pumped off when flooded and wherein the said means do not in any way interfere with the pumping of the well from the bottom when the well is not flooded.

Other objects and advantages will be apparent during the course of the following description.

In the accompanying drawing forming a part of this application and in which like numerals are employed to designate like parts throughout the same,

Figure 1 is a side elevation of a tubing arranged in a well casing and equipped with a plurality of the improved telescopic air valves, the valves being spaced at intervals of approximately 200'.

Figure 2 is a central vertical sectional view through the telescopic air control valve in its closed position.

Figure 3 is a central vertical sectional

view through the telescopic air valve in its 55 open position.

Figure 4 is a horizontal sectional view taken on line 4—4 of Figure 3.

Figure 5 is a vertical sectional view through the control means for the telescopic valves, the view illustrating the means by which the valves may be successively opened or closed.

Figure 6 is a vertical sectional view through a modified form of control means 65 for the telescopic valves.

Figure 7 is a detail elevation taken at right angles to Figure 6 and illustrating the means to indicate the number of valves open.

In the drawings wherein for the purpose of illustration is shown a preferred embodiment of the invention the numeral 5 designates a casing of any suitable diameter and which is adapted to receive the tubing 6 through which the oil flows and is discharged. The lower portion of the tubing is provided with the usual stand pipe 7 mounted upon a wooden block 8 and the upper end of the stand pipe 7 is provided with a perforated inlet nipple 10 through which the oil enters the tubing when the well is pumping from the bottom.

However, it frequently happens that the well floods or the oil level within the casing gets so high that the pressure of the air introduced into the casing from an air compressor will not be sufficient to force the oil through the perforations in the nipple 10 and up through the tubing.

Therefore, I interpose a plurality of telescoping air inlet valves 12 at spaced points in the tubing and provide a means whereby the same may be opened in succession from the top down so as to lower the oil level and permit the pumping to take place from the bottom of the well.

Each telescopic air lift valve is alike and consist of inner and outer tubular sections 14 and 15, the sections having their intermediate portions formed with openings 16 and 17 for the admission of the air pumped into the casing from an air compressor, all of which will be later described. In carrying out the invention the lower portion of the section 14 is provided with a combined attaching and stop nipple 18 which as illustrated in Figure 1 has connection with a

coupling 19. The coupling joins the nipple 18 to the adjacent joint of tubing. The nipple is located in the path of travel of the enlarged lower portion 19 of the section 15 and consequently limits the movement of the section 15 into the section 14. By reason of this construction when the section 15 reaches the limit of its downward movement in the tubular section 14 the perforations 16 and 17 are in register.

When the supporting means for the tubing is properly actuated the tubing is raised from above so that the uppermost telescopic valve will move from the position illustrated in Figure 3 to the position illustrated in Figure 2. When the upper section 15 is elevated the openings 16 and 17 are no longer in register so that the pumping action will take place from the valve immediately below. Furthermore the upper portion of the outer section 14 is provided with an internal contact shoulder 20 having a contact ring 21 of copper or other suitable material arranged in the path of travel of the annular shoulder formed by the enlargement 19, so that the separation of the sections is limited.

In operation the wooden plug 8 is first driven firmly down onto the bottom of the well as shown in Figure 1 and the string of tubing with the telescopic valves interposed therein is then lowered into the well.

Prior to introducing air into the casing the supporting means for the tubing is so positioned that all the valves will be closed and to close the valves, the tubing is of course drawn upwardly so that all the shoulders 19 will be in engagement with the associated contact rings 21. The air is now introduced into the casing and an effort is made to pump the well from the bottom and in case the well is flooded the tubing is lowered slightly from the upper end so that the uppermost valve will open whereupon the pumping action will take place through this air-lift valve. When the oil above the uppermost valve has been pumped off by the air under pressure the tubing is elevated slightly so that the uppermost valve assumes the position illustrated in Figure 2 and the pumping action then takes place through the air lift valve next below and this continues until the well pumps from the bottom.

The supporting means for the tubing and the control means for the several independent valves is illustrated in Figure 5 wherein the numeral 30 indicates a control nipple threaded onto the upper portion of the tubing. Of course the upper portion of the tubing and more specifically the upper joint of the same is cut and threaded at exactly the right place so that the full threads on the control nipple 30 will engage the full threads on a hand wheel 32.

Figure 5 illustrates that the hand wheel 32 is mounted upon an upper race-way 33

and is secured thereto by means of a set screw 34. A second race-way 35 is arranged beneath the first named race-way and anti-friction elements such as ball-bearings 37 are confined between the upper and lower race-ways.

A stout coiled springs 39 supports the race-ways 33, the hand wheel 32 and consequently the entire length of tubing and by observing the expansion and contraction of the coiled spring 39 it is possible to ascertain just which valves are opening and which are closing.

The coiled spring 39 which is capable of supporting the entire string of tubing which weighs 8000 lbs. at the most rest upon a packing nut 40 threaded into the cap 41 of a head 42 on the casing 5. A suitable packing 43 may of course be located within the packing 41 and is tightly engaged with the control nipple 30 by tightening the nut 40.

In carrying out the invention the air inlet head 42 is provided with an air inlet pipe 46 having connection with an air compressor capable of compressing the air around 100 or 125 lbs. A valve 47 is interposed in the air line 46 and forms a means whereby the admission of air into the casing may be manually controlled. An air relief valve 147 is also interposed in the air line 46 between the air inlet head 42 and the valve 47 and forms a means whereby the air may escape when the well is not in operation. If the air were confined in the well under pressure when the well was not in operation the inflow and accumulation of oil in the bottom of the well would be retarded. The drawings and particularly Figure 5 illustrate that an air gauge 48 may be interposed in the air line 106 between the main inlet valve 47 and the head 42.

Figure 5 also illustrates that the upper portion of the control nipple or operating nipple 30 may be provided with a T-coupling 50 having connection with a pipe 51 by means of which the oil may be conveyed to a tank. Of course, a suitable flexible connection is interposed in the line 51 so as to allow a limited upward movement of the operating nipple when the several valves are opened and closed. A testing pipe 53 is extended upwardly from the T-coupling 50 and has a gate valve 54 interposed therein so that a test may be made at any time.

As illustrated in Figure 5 the hand wheel 32 cooperates with a calibrated bar or arm 178 in indicating the number of valves which are open. When the parts are in the position illustrated in Figure 5 all valves are open. As the hand wheel is turned to the right to elevate the tubing the valves will successively close, the top valve closing first. When the hand wheel 32 is opposite number 4 on the arm this will

indicate that there are four valves open. Of course when the hand wheel is opposite the numeral 1 on the arm 178 the operator will know that only the lowermost valve 5 or #1 valve is open.

In the form of the invention illustrated in Fig. 6 the tubing is designated by the numeral 60 and is provided at its upper portion with a coupling 61 to which an 10 oil discharge pipe 62 is connected. Of course the lower portion of the tubing has connection with the telescopic air valve so that the vertical movement of the tubing results in the successive operation of the 15 valve.

Figure 6 illustrates that a cylinder 64 is connected as indicated at 65 to the casing head stuffing box 66 the stuffing box 66 being mounted upon the casing 67 in the 20 usual and well known manner. In carrying out this form of the invention a piston 69 is mounted in the cylinder and is securely connected by screw threads or otherwise to the tubing 60 so that when the piston 25 is elevated the tubing also will be elevated and the valve will be successively opened.

The compressed air supply line 70 extends into the stuffing box 66 and has connection with a pipe 71 through the medium of a branch 2. The pipe 71 has communication with the lower portion of the cylinder 64 so that when compressed air is supplied by way of the pipe 71 the piston 69 will 35 be elevated. A control valve 73 is interposed in the branch 2 and may of course be shut off for shutting off the supply of air to the cylinder. The line 71 is provided with a discharge valve 74 which may 40 be manually operated for releasing the compressed air beneath the piston 69.

The supply of compressed air to the cylinder 64 elevates the piston 69 and the piston carries a quantity of lubricating oil. 45 When the piston reaches the upper portion of the cylinder 64 it will pass an outlet port or release port 76 so that the compressed air will be discharged and the piston 69 allowed to settle beneath the relief port. This prevents the lubricating oil carried by the piston from flowing over the upper end of the cylinder 64.

The tubing when elevated may be locked in this position by a combined hand wheel 55 and cylinder closure 78 which as illustrated in Figure 6 is threaded on the tubing. More specifically after the tubing has been elevated to the proper point it may be locked in this position by turning the hand wheel 60 until it engages the cylinder and by reason of this construction in case leakage of compressed air occurs the tubing cannot settle. Attention is also directed to the fact that the hand wheel 78 extends beyond the cylinder 64 and consequently prevents rain

or other matter from entering the cylinder.

In summarizing it will be seen that after the wooden plug 8 has been inserted the string of tubing with the telescopic air valves spaced about 200' apart is lowered 70 into the well. The last joint of tubing is cut and threaded at such a point that the upper portion of the threads on operating nipple 30 will just engage the full threads of the operating hand wheel. In this position the valves are open.

To close the valves the hand wheel is turned so as to raise the operating nipple until the upper valve closes and so on until the other valves close in succession to the 80 bottom. The reverse operation opens the valves beginning at the bottom and in succession to the top. In operation when the air is turned into the well under 100 to 125 lbs. pressure from a compressor to the air 85 inlet nipple assembly the oil is forced downward in the casing past the closed valves and up into the tubing. The valves should all be closed as this operation is begun in order to see if the well will pump from the 90 bottom. If the well will not pump from the bottom, then the tubing is lowered opening

the lowermost valve first and then the next valve above and so on until the well does 95 pump. As soon as the proper valve is opened where the well will pump, the pumping is allowed to continue from that valve until all the oil above has been blown from the well by air pressure. Then the tubing is raised and the well is pumped from the 100 next valve below and so on until the well may be pumped from the bottom. As soon as the pumper learns the proper intervals for pumping the well he should pump them at such intervals as the well will pump from 105 the bottom. The different depths of the various valves are arranged so that the well may be pumped from any level, in case of flood or for any other reason the well is allowed to rise so high that the well will not 110 pump from the bottom by oil pressure.

The practice now in pumping oil wells with air is to pull the tubing to a higher level when the well floods. This is an awkward and expensive process of setting up 115 the equipment each time to pump from lower levels as the oil is blown from the higher levels, all of which is lacking in this invention.

The bracket or arm 169 is mounted on the 120 member 78 and cooperates with a series of calibrations so as to indicate the number of valves open. When the pointer or indicator of the part 169 is opposite 4, of course the operator will know that only four valves are open and when the indicator is opposite the numeral 2 on the stem 60 the operator will know that only two valves are open. These two, of course, will be the two lowermost valves.

It will be seen that the by-pass valve 73 may be opened for establishing free communication between the main air supply pipe 70 and the cylinder 64. When air is introduced into the cylinder 64 by opening the valve 73 the piston 69 and consequently the tubing 60 is raised to the desired point. The hand wheel 78 is now turned down into engagement with the cylinder 64 to lock the tubing in its elevated position. Of course, when the piston 69 has reached the proper position the valve 73 is closed.

Having thus described the invention, what is claimed is:—

- 15 1. In an air lift valve for well tubings, a pair of telescopic tubular sections having openings adapted for registration, said sections having enlargements arranged in the same vertical planes whereby the separation 20 of the sections is limited, and a contact ring carried by one of the enlargements and adapted for contact by the other enlargement when the openings are out of registration.
- 25 2. An air lift valve for wells comprising inner and outer tubular sections having openings adapted for registration, said inner section being provided with an external enlargement and said outer section being provided with an internal enlargement arranged in the path of travel of said external enlargement whereby the separation of the sections is limited, the external enlargement on said inner section being adapted to extend over and close the openings in the outer section.
- 40 3. A well equipment comprising a string of tubing consisting of a plurality of connected lengths, telescopic air valves interposed in said tubing between said lengths and consisting of slidably connected tubular sections having openings adapted for registration, the sections of said valve being provided with means whereby to limit the separation of the sections and to close the openings in one of the sections, and means whereby to raise or lower the tubing from the upper portion thereof whereby to successively open or close said valves.
- 50 4. A well equipment comprising a string of tubing consisting of a plurality of connected lengths, telescopic air valves interposed in said tubing between said lengths and consisting of slidably connected tubular sections having openings adapted for registration, the sections of said valves being provided with means whereby to limit separation of the sections and to close the openings in one of the sections, means whereby to raise or lower the tubing from the upper portion thereof whereby to successively open or close said valves, and a perforated inlet member connected to the lower portion of said tubing.
- 55 5. A well equipment comprising a string

of tubing consisting of a plurality of connected lengths, telescopic air valves interposed in said tubing between said lengths and consisting of slidably connected tubular sections having openings adapted for registration, the sections of said valves being provided with means whereby to limit separation of the sections and to close the openings in one of the sections, means whereby to raise or lower the tubing from the upper portion thereof whereby to successively open or close said valves, a perforated inlet member connected to the lower portion of said tubing, and a block upon which the tubing rests during the raising and lowering of the upper and intermediate portions of the same.

6. A well equipment comprising a string of tubing consisting of a plurality of joints, telescopic air inlet valves interposed in the tubing between the joints and providing a means whereby a limited sliding connection is provided between the joints of tubing, an operating nipple connected to the upper portion of the tubing, and a hand wheel having connection with the operating nipple and forming a means whereby the operating nipple may be raised or lowered, and a spring supporting the operating nipple and the length of tubing.

7. A well equipment comprising a string of tubing consisting of a plurality of joints, telescopic air inlet valves interposed in the tubing between the joints and providing a means whereby a limited sliding connection is provided between the joints of tubing, an operating nipple connected to the upper portion of the tubing, a hand wheel having connection with the operating nipple and forming a means whereby the operating nipple may be raised or lowered, a spring supporting the operating nipple and the length of tubing, and a casing head having a packing and a packing nut, the packing nut constituting a supporting means for said coiled spring.

8. A well equipment comprising a string of tubing consisting of a plurality of joints, telescopic air inlet valves interposed in the tubing between the joints and providing a means whereby a limited sliding connection is provided between the joints of tubing, an operating nipple connected to the upper portion of the tubing, a hand wheel having connection with the operating nipple and forming a means whereby the operating nipple may be raised or lowered, a spring supporting the operating nipple and the length of tubing, a casing head having a packing and a packing nut, the packing nut constituting a supporting means for said coiled spring, and an air inlet pipe connected to said casing head and having a valve interposed therein.

9. A well equipment comprising a string of tubing consisting of a plurality of joints,

- telescopic air inlet valves interposed in the tubing between the joints and providing a means whereby a limited sliding connection is provided between the joints of tubing, an 5 operating nipple connected to the upper portion of the tubing, a hand wheel having connection with the operating nipple and forming a means whereby the operating nipple may be raised or lowered, a spring supporting 10 the operating nipple and the length of tubing, a casing head having a packing and a packing nut, the packing nut constituting a supporting means for said coiled spring, an air inlet pipe connected to said casing 15 head and having a valve interposed therein, and a relief valve whereby the air in the casing may escape.
10. A well equipment comprising a string of tubing consisting of a plurality of joints, 20 telescopic air inlet valves interposed in the tubing between the joints and providing a means whereby a limited sliding connection is provided between the joints of tubing, an operating nipple connected to the upper portion 25 of the tubing, a hand wheel having con-
- nection with the operating nipple and forming a means whereby the operating nipple may be raised or lowered, a spring supporting the operating nipple and the length of tubing, a casing head having a packing and a packing nut, the packing nut constituting a supporting means for said coiled spring, an air inlet pipe connected to said casing head and having a valve interposed therein, and an oil conducting pipe connected to said operating nipple. 30
11. A tubing elevating and control mechanism for wells comprising a cylinder having means whereby the same may be secured to a casing head, a piston movable in the cylinder, and a tubing having connection with the piston and adapted to be elevated thereby, a combined cylinder closure and hand wheel mounted on said tubing and adapted for holding said tubing in a set 40 position, and means whereby to supply fluid under pressure to said cylinder for actuating said piston, said cylinder being provided with a relief port. 45

ALEXANDER BOYNTON.
